UNITED STATES PATENT OFFICE

HENRY F. STILWELL, OF SAN ANTONIO, TEXAS

MEANS FOR DELIVERY OF MAIL AND OTHER MATTER FROM AEROPLANES WHILE IN MOTION

Application filed August 26, 1929. Serial No. 388,546.

This invention relates to improvements in devices for delivering or releasing mail or the like from an aircraft, while the latter is in flight. It is designed to make it possible 5 to deliver mail, commercial parcels, army emergency supplies, etc., while the craft is in flight, and with the least possible danger to air personnel, and the parcels handled. With my device, mail or other parcels may 10 be delivered while the aircraft is travelling at any speed, and allow the mail or other parcels to be deposited on the landing surface practically at any desired point.

The primary object of the invention is 15 to provide a release device designed to be suspended from a rope or cable having its upper end wound about a drum on the aircraft, and the device being so constructed as to instantaneously release mail or the like, 20 as soon as the device strikes a package landing surface over which the craft is flying.

With the foregoing objects outlined and with other objects in view which will appear 25 as the description proceeds, the invention consists in the novel features hereinafter described in detail, illustrated in the accompanying drawings, and more particularly pointed out in the appended claims.

Referring to the drawings,

Fig. 1 is a side elevation of my device.

Fig. 2 is a similar view but taken at right angles to Fig. 1.

Fig. 3 is a top plan view of the same.

Fig. 4 is a horizontal sectional view on the line 4—4 of Fig. 1.

Fig. 5 is a vertical sectional view of the device.

Fig. 6 is a diagrammatic view of an aero- 40 plane in the act of delivering a sack of mail by means of my device.

It will be seen from the drawings that the device comprises a central frame, column or post 6, having a cylindrical bore 7 extending 45 vertically therethrough and merging at its upper end into a cross groove 7a.

Upper and lower pairs of cross arms 8 and 9 cross one another and have their central portions connected to the central frame by 50 mortise joints 10.

The outer ends of these arms carry shafts or bolts 11 on which intermediate portions of legs 12, 13, 14 and 15 are fulcrumed, and these fulcrums allow the legs to rock back and forth relatively to the central frame. However, for the purposes of the present invention, it is necessary that these legs swing in unison, so that when the lower end of either one of the legs strikes against the ground surface, while the device is suspended from an 55 aircraft, all of the legs will rock on their fulcrums to the same degree as the leg which has struck the ground. For this purpose, the upper end of the leg 12 is provided with a pair of pivotally mounted arms 16 which project toward the central frame and carry at their ends cams 17 which slide in dove-tail grooves on the central frame. These cams slide against fixed cams 17a which are rigidly connected to the inner surfaces of the upper 60 ends of the legs 13 and 15. From this it will be seen that when the upper end of the leg 12 swings away from the central frame, the cams will cause the upper ends of the legs 13 and 15 to swing away from the frame an equal 65 amount.

The leg 13 is also provided above its fulcrum with a similar pair of pivotally mounted arms 18 carrying movable cams 19 which slide in dove-tail grooves 20 in the central frame, 70 and coact with fixed cams 21 that are rigidly mounted on the inner surfaces of the legs 12 and 14.

The cams 17 and 17a are maintained in engagement by a coiled spring 22 which has its 75 ends connected to the legs 13 and 15, and the other cams 19 and 21 are maintained in engagement by a coiled spring 23, which has its ends connected to the legs 12 and 14 above the fulcrums of the latter.

Below the fulcrums, the diametrically opposite legs are connected together by linkage 24 and 25. Each said linkage preferably comprises a central link 26 which has its intermediate portion pivotally connected to the 85 center post, and its opposite ends pivotally connected to links 28 and 29 that are pivotally connected to opposite ones of the legs.

The lower end portion of each leg is provided with a guard 30 consisting of oppo- 90

sitely extending arms 31; and the arms of adjacent legs alternate, so that when the lower ends of the device collapse under a blow which is struck when the device hits the ground, these arms will not interfere with one another. Furthermore, these arms provide a pen or confining means for a mail sack 33 or the like, which is to be delivered by the structure.

10 The mail sack or similar article to be released by my mechanism is connected to a delivery rod 36 which is threaded upwardly through the bore 7 of the center post, and is provided at its upper end with a hook 38 that is designed to rest upon a sliding pin 39 which is pivotally mounted on the arm 15, and slides horizontally in a hole which extends laterally through the post toward the bore of said post.

15 For the purpose of suspending the device from an aeroplane or the like, the top of the post 6 may be provided with a bail 40 connected to one end of a rope or cable 41. The opposite end of the rope will be connected to the aircraft, but is preferably wound upon a drum on the latter. In practice, the device will be arranged aboard the aircraft, and when it is to be used, the operator ties a mail bag or any other package on to one end of the delivery rod 36, and then the hook end of this rod is threaded into the lower end of the bore of the central post, and the hook 38 is engaged with the sliding pin 39. Then, if the device is lowered, it will, due to the pressure of the air, as the aircraft moves forwardly, assume an inclined position, (see Fig. 6), with the lower end of one or the other of its legs arranged nearer the ground surface than some of the other legs. Consequently, when the aircraft flies sufficiently low over the spot where the mail or the like is to be delivered, the lower end of one or the other of the legs will strike the ground. The resulting impact will cause that leg to rock on its fulcrum, and as all of the legs are interconnected for joint movement in the manner heretofore described, obviously, all of the legs will swing about their fulcrums to the same degree, with the result that the sliding pin 39 will be withdrawn from the bore of the central post, and thus release the hook 38 on the delivery rod, so that the mail sack, and the delivery rod will be deposited on the landing surface. After delivery, the rope from which the device is suspended, will be raised into the aeroplane, and the parts will be returned to normal position under the influence of the coiled springs 22, 23. Therefore, as soon as the device is again elevated into the aircraft, it will be in readiness for attachment to another one of the package delivery rods 36.

To prevent the upper ends of the legs from swinging outwardly while the device is being manipulated within the aircraft, I prefer to provide the device with some means for

latching the legs temporarily against movement. Such means may consist of an L-shaped arm 45 which is pivotally connected at 46 to the upper end of the central post, and is adapted to swing over and engage the upper end of the leg 15. As all of the legs are constrained to move in unison, it is apparent that this single latch will function to secure all of the legs temporarily against movement.

I also prefer to provide the device with means to limit the collapsing movement of the legs. Such means may comprise a stop 50, rigidly mounted on the leg 15, and adapted to impinge against the central post when the upper ends of the legs are swung outwardly.

From the above description, it is believed that the construction, operation and advantages of the invention may be readily understood by those skilled in the art, and it is manifest that the parts may be made of any suitable material or dimensions, and that changes may be made in the details disclosed, without departing from the spirit of the invention, as expressed in the claims.

What I claim and desire to secure by Letters Patent is:

1. A parcel delivering device for aircraft, comprising a plurality of relatively movable members forming a collapsible package enclosure, means for supporting a package within the enclosure, and mechanism actuated by the movement of any one of said members for releasing the package from said supporting means.

2. A package delivering device for aircraft, comprising a plurality of relatively movable members, means for supporting a package to be delivered, and mechanism associated with and actuated by the movement of any one of said members for releasing the package from the supporting means.

3. A package delivering device for aircraft, comprising a frame, a plurality of leg members pivotally connected to the frame and movable relatively to one another, a package support on the frame, and means for releasing the package from its support upon movement of any one of said members.

4. A package delivering device for aircraft, comprising a frame, a plurality of similar members pivotally mounted on the frame, means operatively connecting said members for causing all of said members to move in unison when any one of the members is moved, a package support on the frame, and means for causing the package to be released from said support upon movement of any one of said members.

5. A package delivering device for aircraft, comprising a frame, a plurality of similar legs pivotally mounted on the frame, means for causing all of said legs to move in unison when any one of the legs is moved, a pack-

- age support on the frame, and means for causing the package to be released from said support upon movement of any one of said legs.
- 5 6. A package delivering device for aircraft, comprising a central frame, legs pivotally mounted on the frame and arranged at different angles around the frame, means for causing all of said legs to move when any 70
10 one of the same is moved, a package support carried by the frame, and means for releasing the package support upon movement of any one of said legs.
- 15 7. A package delivering device for aeroplanes, comprising a central frame, legs pivotally connected to said frame, means for causing said legs to move in unison when any one of the legs is moved, said means including cams movable with one of the legs, and 80
20 cooperating cams on others of the legs, a package support carried by the frame, and means for causing a package to be released from the support upon movement of any one of said legs.
- 25 8. A device for delivering mail or the like from an aircraft, comprising a frame, relatively movable members pivotally connected to the frame and projecting from the latter, means for causing said members to move in 85
30 unison when any one of said members is moved, a package support, and means for moving the package support out of supporting position upon movement of any one of said members.
- 35 9. A package delivering device for aircraft, comprising a frame, legs pivotally connected intermediate their ends to said frame, means for causing said legs to swing in unison when any one of the legs is swung about 90
40 its fulcrum, a package support, and means for moving said support out of supporting position upon the movement of any one of said legs relatively to the frame.
- 45 10. A package delivering device for aeroplanes, comprising a frame having a bore adapted to receive a hooked package supporting rod, a support designed to carry said rod, relatively movable members connected to said frame, means for causing all of the 95
50 members to move in unison when any one of the members is moved, and means for withdrawing the support from supporting position when any one of said members is moved relatively to the frame.
- 55 11. A device for delivering packages from aircraft, comprising a central frame having supporting arms projecting therefrom at angles to one another, legs pivotally connected to said arms, resilient means functioning to yieldingly force one end of each arm toward the frame, means for causing the last mentioned ends of the legs to move away from the frame upon movement of the opposite end of any one of the legs in the opposite 100
60 direction, and a package support arranged 110
65
- 70 on the frame and adapted to be moved out of supporting position upon movement of any one of said legs.
- 75 12. A package delivering device for aircraft, comprising a central frame provided with a supporting pin, arms projecting from the frame, legs pivotally connected to said arms, one of said legs being operatively connected to said supporting pin, resilient means normally forcing the upper ends of the arms toward the frame, cams mounted on the legs for causing the upper ends of the legs to move away from the frame in unison when any one of said legs is moved in a certain direction, and links pivotally connecting the legs and 115
80 frame and arranged below the points where the legs are pivoted to the frame.
- 85 13. A mail delivering device comprising a central frame provided with a movable support, legs arranged around the frame and having their intermediate portions pivotally connected to the frame, means for causing the legs to move in unison when any one of the legs is moved, and guards arranged on the lower portion of each leg, the guards of adjacent legs overlapping one another. 120
90
- 95 14. A device for releasing packages from an aircraft, comprising a frame, legs having their intermediate portions pivotally connected to the frame, means for causing said legs to move in unison about their fulcrums when any one of the legs is swung about its fulcrum, a package support on the frame designed to be moved out of supporting position when any one of the legs is swung about its pivot, and latching means arranged on the frame and engaging one of the legs for temporarily preventing the legs from swinging on their pivots. 125
100
- In testimony whereof I affix my signature. 10.
